BY *H. Kenton Langford*

ATTORNEY

UNITED STATES PATENT OFFICE.

EUGENE ARSÈNE DIFFINGER, OF PARIS, FRANCE, ASSIGNOR TO ETABLISSEMENTS P. COLOMBIER, FILS, OF PARIS, FRANCE.

THERMOSTAT.

Original application filed August 18, 1923, Serial No. 658,138. Divided and this application filed May 2, 1924. Serial No. 710,671.

To all whom it may concern:

Be it known that I, EUGENE ARSÈNE DIFFINGER, a citizen of the French Republic, and residing at the city of Paris, Republic 5 of France, have invented certain new and useful Improvements in Thermostats, of which the following is a specification.

This invention relates to a thermostat, and particularly to a type of thermostat 10 adapted for use in connection with refrigerating apparatus, the operation thereof being controlled by the temperature of the gas circulating between a rotary compressor and a condenser.

15 This application is a division of my co-pending application Serial No. 658,138 filed August 18th, 1923, and covering a rotary compressor operated in oil to circulate a refrigerating fluid in an evaporating apparatus 20 while cooling brine is circulated around the same in a direction opposite to the travel of the refrigerating fluid, after which the compressed fluid is liquefied for further compression.

25 Among the advantages of this device are its automatic control, its precise accuracy secured through the differences of pressure between a condensing device and an evaporating device, it being necessary in this 30 type of refrigerating apparatus that the weight of the refrigerating fluid entering the evaporating device shall equal the weight of what is withdrawn from the evaporating device by the compressor preparatory to compression and delivery to the condensing apparatus, thereby controlling 35 the opening in a regulating cock.

In the preferred form shown herewith, 40 my device is shown as it would be constructed for attachment to such a rotary refrigerating apparatus but it can also be used in many other constructions where temperatures are available as operative means.

45 The invention is more fully described in the following specification and shown in the drawing in which:—

The figure is a vertical sectional view of the thermostat.

As shown herewith the device consists of a light weight metal cylinder 6 containing a liquid the boiling point of which is slightly higher than the temperature of the

gas compressed in the normal operation of 55 the machine.

This cylinder may be secured in any suitable way to the pipe which connects the compressor and condenser in a refrigerating apparatus where it will constantly be 60 surrounded by the high temperature compressed gas and it also communicates by the flexible tube 7 with the chamber 8 which contains mercury and may be connected with the said condenser through the conduit 9.

The upper end of the cylinder 8 is secured in the base of the bell shaped chamber 10 containing a float 11 the interior of which is connected with the cylinder 8 by the 70 spiral tube 12, the open lower end of which is positioned near the bottom of the cylinder 8.

Above the chamber 10, the conduit 13 having an orifice 14 for communication with 75 the evaporating device of the refrigerating apparatus is arranged, and within the said conduit the piston 15 is held by the spiral spring 16 against the float 11, the spring 16 being adjustable by the screw threaded ring 80 17. The screw cap 18 provided with packing, acts as a tight closure of the top of the device.

In the said piston 15 the triangular groove 19 connects the interior of the bell 85 10 with the conduit 13.

The operation is as follows; variations in the temperature of the compressed gas affect the vapor in the cylinder 6 which by expansion will pass through the tube 7 into 90 the cylinder 8 and cause a displacement through the spiral tube 12 of the mercury in the float 11, whereby the weight of the said float will vary and affect the extent of the opening in the groove 19 by the piston 95 15. When the temperature of the gas increases, the mercury in the cylinder 8 flows slowly into the float 11 which sinks by gravity and permits the downward movement of the piston 15 and the passage of an increased amount of the liquid in the chamber 10 through the groove 19 in the piston 15. The reverse occurs when the temperature of the compressed gas is lowered.

I claim:—

1. In a thermostatic regulator for the control of the flow of liquids, the combina-

tion of the following elements; a container provided with a liquid adapted to be vaporized; a second container provided with mercury; a pipe connection between the said 5 two containers; a chamber provided with an inlet and an outlet; a float within said chamber; a pipe connection between the mercury in the said second container and the said float; a conduit connected with the 10 said chamber and provided with an outlet; and a piston mounted in the said conduit and having a groove in its lower end, the said piston being in engagement with the said float and adapted to move therewith.

2. In a thermostatic regulator for the 15 control of the flow of fluids, the combination with a refrigerating fluid chamber provided with an inlet and an outlet for said fluid, means located in the outlet adapted to control the flow of said fluid through said 20 chamber, a float in the chamber co-acting with the said means, a mercury container, means connecting it to the said float, and temperature responsive means for transferring mercury from the mercury chamber to 25 the float.

EUGENE ARSÈNE DIFFINGER.
